CLAIM

The ornamental design for an electronic cutter, as shown and described.

DESCRIPTION

FIG. 1 is a perspective view of an electronic cutter, showing our new design;
 FIG. 2 is a front elevation view thereof;
 FIG. 3 is a top plan view thereof;
 FIG. 4 is a right-side elevation view thereof;
 FIG. 5 is a left-side elevation view thereof;
 FIG. 6 is a rear elevation view thereof;
 FIG. 7 is a bottom plan view thereof; and,
 FIG. 8 is a perspective view thereof in an open position in order to show aspects of the design not otherwise apparent. The broken lines immediately adjacent to the shaded areas represent the bounds of the claimed design, while all other broken lines are directed to environment. In addition, the unshaded surface that directly adjoins the solid line edge in FIGS. 6 and 8 forms no part of the claimed design. The broken lines form no part of the claimed design.
